UNITED STATES PATENT OFFICE.

JOHN F. O'CONNOR, OF CHICAGO, ILLINOIS, ASSIGNOR TO WILLIAM H. MINER, OF CHAZY, NEW YORK.

SPRING-DAMPENER.

1,255,214.

Specification of Letters Patent. Patented Feb. 5, 1918.

Application filed September 5, 1916. Serial No. 118,413.

To all whom it may concern:

Be it known that I, JOHN F. O'CONNOR, a citizen of the United States, residing at Chicago, in the county of Cook and State 5 of Illinois, have invented a certain new and useful Improvement in Spring-Dampeners, of which the following is a full, clear, concise, and exact description, reference being had to the accompanying drawings, forming 10 a part of this specification.

This invention relates to improvements in spring dampeners.

The object of the invention is to provide a spring dampener suitable for use in draft 15 riggings or other places where heavy shocks are encountered and which shall consist of few parts, simply arranged to effectively minimize the recoil after the pressure on the parts has been released.

20 In the drawing forming a part of this specification, Figure 1 is a horizontal sectional view of a draft rigging showing my improvements adapted therefor, the parts being in full release. Fig. 2 is a view similar to Fig. 1 but illustrating the position 25 of the parts under full compression. And Fig. 3 is a vertical, transverse sectional view taken on the line 3—3 of Fig. 1.

In said drawing, 10—10 denote channel, 30 center or draft sills, the same having secured to their inner faces rear stops 11 and front stops 12 with which coöperate a rear follower 13 and a front follower 14, respectively. For operating the gear, a yoke 15 35 is provided which surrounds the followers and dampener between the followers, said yoke being riveted or otherwise suitably secured to a draw bar 16. All the foregoing parts are, or may be, of well known or de- 40 sirable construction.

The improved spring dampener, which is shown adapted for use in a draft rigging, comprises a pair of oppositely disposed, preferably counterpart cast heads 17—17; plates 18—18; a spring 19; and a casing 20. Each of the heads 17 is preferably of substantially cylindrical form, as clearly indicated in Fig. 3, and on its inner face is provided with a recess of parti-cylindrical form 45 with the axis of the cylinder extending in a horizontal plane at an angle to the axis of the gear. This recess designated 21 has its bottom face curved as indicated at 22 and against which bears one of said plates 18, 50 each of the plates 18 having a correspond- 55 ingly curved outer face 23. The spring 19, as shown, consists of an outer heavy coil 24, intermediate coil 25 and inner coil 26, the latter being seated at its ends on suitable bosses 27 formed on the inner faces of the 60 plates 18. The inner faces of each of the heads 17 are disposed at an angle to the axis of the gear as indicated at 28, this being done in order to provide a larger surface for the plate 18 to work upon, as will be 65 understood from the position of the parts shown in Figs. 1 and 2. The heads 17—17 are surrounded by the casing 20 which preferably is in the form of a steel tube, said casing overlapping each of the heads 17. To 70 maintain the casing in proper position relatively to the heads 17—17 and also to limit the separation of the latter, each of the heads 17 is provided with a longitudinal slot 29 on its exterior in which reciprocates 75 the inner end of a bolt or pin 30 secured to the casing.

The normal position of the parts is as shown in Fig. 1, wherein the heads 17—17 are separated a distance equal to the length of 80 stroke of the gear. Upon either buff or draft, it is apparent that the heads 17—17 will be moved toward each other and as this action occurs, the plates 18—18, together with the spring 19 will be rotated or oscillated about 85 an axis which is perpendicular to a plane extending horizontally and parallel to the center line of the gear. During this oscillating or turning movement of the plates and spring, the plates 18 will, of course, 90 slide on the surfaces 22 and at the same time the spring will be compressed until finally the condition is reached which is shown in Fig. 2. The relative approach of the heads 17—17 is limited both by their engagement 95 with each other and also by the engagement of the casing 20 at both ends with the followers 13 and 14. It will also be noted that, as the heads 17—17 approach each other, there is a tendency to shift the same laterally relative to each other. This causes the heads 17—17 to frictionally engage the casing 20 during the sliding movement, one 100 of said heads being forced against the casing on one side and the other head against the casing on the opposite side, as indicated in Figs. 1 and 2. Upon release of the pressure, the spring 19 will expand and in so doing it will force the heads 17—17 apart. During this expanding action, it is apparent 105 110

that the heads 17—17 will frictionally engage the casing 20 and at the same time the plates 18 will slide with respect to the heads 17. The amount of friction generated in this release action automatically and efficiently serves to dampen the recoil, to thus minimize the recoil shock and prolong the life of the parts.

Although I have herein shown and described what I now consider the preferred embodiment of the invention, the same is merely illustrative and I contemplate all changes and modifications coming within the scope of the claims appended hereto.

15 I claim:—

1. In a spring dampener, the combination with a pair of oppositely arranged, normally separated heads, the latter having recesses on their opposed faces, each recess 20 having a concave friction surface, of plates frictionally engaging said surfaces and hav-

ing convex friction surfaces, a spring extending between said plates, and a floating casing encircling said heads, said heads frictionally engaging said casing upon relative longitudinal movement between the heads.

2. In a spring dampener, the combination with a pair of heads relatively longitudinally movable, said heads having recesses on their inner faces, of plates slidably mounted within said recesses, a spring extending between said plates and adapted to be compressed upon relative approach of the heads, and a longitudinally movable casing encircling the heads and frictionally engaging the latter upon relative longitudinal movement thereof.

In witness that I claim the foregoing I have hereunto subscribed my name this 31st day of August 1916.

JOHN F. O'CONNOR.
